UNITED STATES PATENT OFFICE.

MILTON C. SUPAN, OF RED BLUFF, CALIFORNIA.

GATE-OPERATING MECHANISM.

1,162,954.

Specification of Letters Patent.

Patented Dec. 7, 1915.

Application filed January 23, 1915. Serial No. 3,976.

To all whom it may concern:

Be it known that I, MILTON C. SUPAN, a citizen of the United States, residing at Red Bluff, in the county of Tehama and State of California, have invented certain new and useful Improvements in Gate-Operating Mechanism, of which the following is a specification, reference being had to the accompanying drawings.

10 My invention relates to gates, and particularly to gate operating mechanism, and the primary object of the invention is the provision of mechanism whereby a gate may be opened from a distance and by persons 15 riding in a vehicle.

A further object of the invention is the provision of means whereby the gate may be opened, partly through the action of gravity and partly through the action of suitable 20 operating levers.

A further object of the invention is to provide a gate of the character described and an operating mechanism therefor so constructed that a strain will be placed 25 upon the gate which will cause it to open immediately after the proper latch is released, and provide means for releasing the latch.

A further object is to simplify the construction of gates of this character and increase their effectiveness.

Other objects will appear in the course of the following description.

My invention is illustrated in the accompanying drawings, wherein—

Figure 1 is a perspective view of a gate constructed in accordance with my invention; Fig. 2 is a detail horizontal section looking down upon the lower end of the 40 yoke and showing the lower bar for the pintle; Fig. 3 is a fragmentary elevation enlarged of the rear portion of the gate, the adjacent gate post, and the swiveled bearing for supporting the gate upon the gate post; Fig. 4 is a fragmentary section of the auxiliary post 6 and the upright 2, the section being taken just above the latch 10; Fig. 5 is a fragmentary section on the line 5—5 Fig. 2; Fig. 6 is a section through the 45 wheel 21; Fig. 7 is a fragmentary perspective view showing the upper end of the yoke and the pintle extending therefrom. Fig. 8 is a sectional view on the line 8—8 of Fig. 2.

50 Referring to these figures, 2 and 3 designate opposite gate posts, which may be made

of any suitable material, but preferably are made of angle iron, this angle iron being extended across so as to connect the gate posts by a transverse brace 4, and preferably this angle iron also extends across the bottom of the gate to provide a transverse brace 5. Disposed in conjunction with the post 2 or upright is an auxiliary gate post 6 which may be made of wood, cement, or other 65 suitable material and which is attached to the post 2, and which has at its lower end the transversely extending anchoring plate 7. A transversely extending anchoring plate is also attached preferably to the brace 70 5. These plates are to be embedded in the ground so as to be perfectly rigid.

Attached to the standard or post 3 and extending in line therewith is a yoke 9, the upper and lower ends of which are inwardly bent as at 10. The upper inwardly turned end of the yoke is formed with a perforation 11 and the lower inwardly turned end is formed with an elongated slot 12 or recess having a concavely curved bottom 13 forming a seat for the lowermost gate pintle.

The gate 14 is cut away as at 15, and extending downward through the rear end of the gate and therefore through this cut 85 away or open portion 15 and mounted rigidly upon the gate is a pintle 16, the upper end of which extends through the opening 11 and the lower end of which is rounded and rests in the seat 13. Thus it will be seen 90 that the lower end of the pintle has sliding movement in the slot or recess 12 and upon the curved seat 13, the opening 11 being sufficiently large to permit the oscillation of the pintle 16 for a purpose to be later described. The gate is normally held closed by means of oppositely disposed latches 17, 95 these latches being pivoted one on each side of the auxiliary post 6 and each latch having an outwardly extending beveled lug 18. 100 The latches are guided in their movement by the keepers 19.

For the purpose of actuating the gate I mount upon the uprights 2 and 3 the transverse shaft 20 which carries at one end the 105 relatively large grooved wheel 21 and upon its other end a spool 22, both the wheel and the spool being rigidly attached to the shaft 20. Rigidly mounted upon the upright 3 and the yoke 9 is the transversely extending cross bar 23, and pivoted to the opposite ends of this cross bar are the upwardly ex-

tending levers 24 and 25, these levers being identical in form. To the lower end of the lever 25 is attached a cable 26 which extends to and is coiled around the pintle 6 and then extends to the lever 24. The levers 24 and 25 are connected at their upper ends by means of a link 27 which is pivoted to the levers to connect them for common movement, and it will thus be seen that upon 10 a movement of both levers in one direction the cable 26 will be drawn in one direction, causing the rotation of the pintle 16 and of the gate in one direction, while upon a movement of the upper ends of the levers 15 in the opposite direction the gate will be swung oppositely. The upper ends of the levers 24 and 25 are connected by means of a cable 28 which is wrapped or coiled around the spool or drum 22. Thus the 20 rotation of the shaft will cause the oscillation of the levers in one or the other direction. This rotation of the shaft 20 is accomplished by means of cables passed over the grooved wheel 21.

25 Pivotedly mounted upon the upright or post 2 above the wheel 21 is a rocking lever 29 which extends out on each side beyond the wheel 21, the ends of the rocking lever being provided with inwardly projecting pins 30. A cable having two ends 31 and 32 is wrapped around the grooved wheel 21, each end of the cable passing over one of the pins 30 and extending up the road and passing over a pulley 33 mounted upon a post 34, the depending end of the cable being disposed adjacent the road so that it may be conveniently grasped by those approaching the gate in automobiles or other vehicles. Springs 35 are attached to the upper end of 30 the upright 2 or to the cross bar which extends downward and outward, and are connected at their extremities to the extremities of the lever 29. Attached to the rocking lever 29 are cords or cables 36 which extend 35 downward to the latches 17. Thus when one end of the rocking lever 29 is raised the corresponding latch will be raised, and vice versa. The latches, however, it will be seen are operable independently of the rocking lever. The gate 14 is preferably connected 50 to the yoke 10 at its middle by means of a swivel connection 37 which will permit the lower end of the cable 16 to oscillate in the groove or recess 12 and at the same time permit the gate to swing with its pintle in a horizontal plane.

55 The operation of my invention will be obvious from what has gone before. The operator draws upon one of the cords or cables 31 or 32. This will cause a depression of the corresponding end of the lever 29 and this draws upward on the opposite latch. A continued pull on the cord or cable causes a rotation of the shaft 20. This causes the 60 levers 24 and 25 to rock, drawing the cable

26 in one direction or the other depending upon the direction of rotation of the shaft 20 and depending upon which of the cords or the cables 31 or 32 is pulled. When the strain is thus applied to the cable 26 it 70 will first cause the gate to rock in a plane transverse to the plane of the gate when closed and cause the lower end of the pintle to move in the direction away from that in which the gate is to open. The lower end 75 of the pintle will thus ride up the inclined bottom 13 of the seat or bearing 12 thus causing the gate to be thrown out of plumb and overbalancing it. As soon as the pintle has reached the end of the seat 12 toward 80 which it is moving the strain on the cable 26 will rotate the pintle and the gate will thus be opened both by the pull on the actuating cable 31 or 32 and by the action of gravity on the overbalanced gate. The 85 weight of the gate thus helps to open it and thus no great amount of strain will be placed upon the cables 31 or 32. In closing, the lower end of the pintle 16 tends to slide 90 down this inclined bottom to a middle position so as to bring the gate back to a vertical position as the pintle is reversely rotated by the operating means. To close the gate one of the cords 31 or 32 is pulled and as the gate closes the upper edge of the 95 gate will lift the latch permitting the entrance of the gate into the space between the latches, the gate striking the latch on the opposite side and stopping while the first named latch falls to its locked position. It 100 will be understood of course that the framework of the gate should be made of sufficient height to permit the passage of a loaded wagon beneath it.

While I have illustrated what I regard 105 as the preferable form of my invention, it will be obvious that many changes may be made therein without departing from the spirit thereof.

Having described my invention, what I 110 claim is:

1. A gate structure including an upright, a gate mounted thereon for oscillation in a plane at right angles to the plane of its closed position, a supporting pintle depending from the gate at its hinged end, a bearing member disposed below the lower end of the pintle and having a recess whose bottom is concavely curved in a direction transverse to the plane of the gate in its normal position and upon which the lower end of the pintle rests, and actuating means for shifting the pintle and gate in a direction away from the direction in which the gate is to open to overbalance the gate and then rotating the pintle to cause the gate to swing to its open position, the pintle riding downward to the middle of the recess upon a reverse action of the actuating means.

2. A gate structure including oppositely 130

- disposed uprights, a gate swingingly mounted upon one of said uprights and being oscillatable in a vertical plane at right angles to the plane of the closed position of the 5 gate, latches mounted upon the other upright and normally holding the gate in its closed position, a pintle mounted upon the hinged end of the gate, oppositely disposed vertical levers mounted on opposite sides of 10 the first named upright, a cable wound upon the pintle of the gate and connected at its opposite ends to said levers, a shaft operatively supported on the uprights, a cable connecting the upper ends of the levers and 15 coiled around the shaft, a wheel mounted upon the shaft, flexible actuating connections passing from said wheel, supporting means for the ends of said flexible connections whereby an actuation of one or the 20 other of said connections will cause the rotation of the shaft in one or the other direction and the consequent oscillation of the gate, and means operatively connected to said shaft for raising one or the other of the 25 latches upon a rotation of the shaft in one or the other direction.
3. In a gate structure, oppositely disposed uprights, a gate, a pintle for the gate rotatably mounted upon one of said uprights, 30 oppositely disposed latches pivotally mounted upon the other upright, a rocking lever pivotally mounted upon the last named upright and having connections to said latches, springs normally holding said rocking lever 35 in initial position, vertically disposed levers mounted upon the first named upright and pivoted intermediate their ends, a flexible connection attached to the lower ends of said levers and coiled about the pintle of the 40 gate, a shaft mounted in the uprights and having a spool thereon, a flexible connection connecting the upper ends of the levers and coiled about said spool, a grooved wheel mounted upon the shaft, and flexible actuating 45 cables passing over said grooved wheel, said cables being operatively connected to the rocking lever whereby strain exerted upon one or the other of the cables will oscillate the lever to raise the corresponding latch and rotate the shaft to swing the gate. 50
4. A gate structure including an upright, an upper and a lower bearing carried by the upright, a gate mounted for swinging movement upon said upright and for oscillation in a vertical plane at right angles to the plane of the closed position of the 55 gate, a pintle carried by the gate and depending below it, said lower bearing having a pintle seat formed with a concavely curved bottom extending in a direction at right angles to the plane of the gate when closed and supporting the lower end of the pintle, oppositely disposed vertical levers mounted on each side of the uprights and pivoted intermediate their ends, a flexible connection connecting the lower ends of the levers and coiled around said pintle, and manually actuatable means for oscillating said levers to oscillate the gate and draw the lower end of the pintle to one end of said recess and 60 then rotate the pintle and gate to thereby cause the opening thereof. 65
5. In a gate structure of the character described, a gate, an upper bearing and a lower bearing, a vertical pintle upon which the 70 gate is supported, said pintle having oscillation in the upper bearing, and resting loosely at its lower end upon the lower bearing, said lower bearing having a pintle seat concavely curved in a direction transverse 75 to the closed position of the gate, the lower end of the pintle having sliding engagement with said seat and manually operable actuating means operatively connected to the pintle and when actuated drawing the pintle 80 from a median position to one end of the seat to thereby cause the overbalancing of the gate, said means then acting to rotate the pintle to thereby rotate the gate to its 85 open position. 90

In testimony whereof I hereunto affix my signature in the presence of two witnesses.

MILTON C. SUPAN.
